UNITED STATES PATENT OFFICE.

GEORGE H. HAYES, OF HAZELTON, KANSAS.

MANIFOLD FOR EXPLOSIVE-ENGINES.

1,265,779.

Specification of Letters Patent. Patented May 14, 1918.

Application filed August 13, 1917. Serial No. 186,069.

To all whom it may concern:

Be it known that I, GEORGE H. HAYES, a citizen of the United States, residing at Hazelton, in the county of Barber and State 5 of Kansas, have invented a certain new and useful Improvement in Manifolds for Explosive-Engines, of which the following is a specification.

My invention relates to improvements in 10 manifolds for explosive engines.

The object of my invention is to provide novel means for heating and vaporizing fuel for an explosive engine which will afford a maximum of efficiency to the fuel, which 15 will afford economy in the consumption of fuel, which is simple in construction and cheap to manufacture.

The novel features of my invention are 20 hereinafter fully described and claimed.

In the accompanying drawings which 25 illustrate the preferred embodiment of my invention,

Figure 1 is a side elevation of an explosive engine provided with my improvement.

Fig. 2 is a top view, partly broken away, 30 of what is shown in Fig. 1.

Fig. 3 is a vertical sectional view on the line 3—3 of Fig. 2.

Fig. 4 is a vertical sectional view on the 35 line 4—4 of Fig. 1.

Fig. 5 is an enlarged horizontal sectional view on the line 5—5 of Fig. 1.

Similar reference characters designate 40 similar parts in the different views.

1 designates the body of an ordinary four cylinder explosive engine provided with the usual intake ports 2 and exhaust ports 3.

4 designates a manifold casing having a horizontal longitudinal partition 5, Fig. 3, 45 which forms a compartment 6 having an inlet 7 for water and an outlet 8 for steam.

7^a and 7^b designate respectively two partitions disposed parallel with the partition 5. 8 and 9 designate two transverse partitions 50 connecting the partition 7^a with the partition 5 and forming therewith a chamber 10. 11 and 12 designate two transverse partitions connecting the partition 7^b with the partition 5 and forming therewith a chamber 13.

14 designates a conductor having two branches 15 and 16 which respectively discharge into the chambers 10 and 13. A transverse partition 17 connects the conductor 55 14 and the partition 5, thereby forming two chambers 18 and 19.

A passage 20 connects with two inlet ports 21 and 22 located at the outer sides of the chambers 10 and 13, said inlet ports communicating respectively with the two outer 60 exhaust ports 3. The casing 4 is provided with two inlet ports 23 and 24 which respectively connect with the two inner exhaust ports 3.

Two passages disposed at opposite sides of 65 the branch 15 and designated by 25 and 26 connect the passage 20 with the chamber 18. Two passages 27 and 28 disposed at opposite sides of the branch 16 connect the passage 20 with the chamber 19.

The casing 4 is provided with two outlet ports 29 and 30 respectively connecting with the two ports 2.

The casing is provided with an outlet port 31, Fig. 5, which communicates with the 75 passage 20.

The casing 4 is provided with a passage 32 which discharges into the conductor 14 and into which discharges two carbureters 33 and 34. A discharge conductor 35 connects with the outlet port 31. Alongside of the conductor 35 is a conductor 36 adapted to be heated by the conductor 35 and adapted to convey fuel oil. A conductor 37 discharges into the conductor 36, and a conductor 38 connects the conductor 36 with the carbureter 33. A conductor 39 is connected with the passage 32 and with the outlet 8.

A conductor 40 is connected with the carbureter 34 and is adapted to convey gasoline 90 to said carbureter.

Bolts 41 secure the casing 4 to the engine 1. A conductor 42 discharges into the inlet 7 and is connected with a source of water supply.

In the operation of my invention, gasoline 95 is permitted to enter the carbureter 34 through the conductor 40. The explosive mixture passes from the carbureter 34 through the passage 32, conductor 14, and branches 15 and 16 into the chambers 10 and 13 and thence through the ports 29 and 30 into the four engine cylinders through the bifurcated ports 2. The exhaust from the engine cylinders passes through the ports 105 3, thence through the ports 21, 22, 23 and 24 into the passage 20 and chambers 18 and 19, and from the latter by the passages 25, 26, 27 and 28 into the passage 20. The exhaust gases pass from the passage 20 through the 110 outlet 31 into the exhaust discharge conductor 35. The exhaust gases in the pas-

sage 20, chambers 18 and 19 and passages 25, 26, 27 and 28 heat the conductor 14 and its branches 15 and the chambers 10 and 13, thereby highly heating the explosive 5 charges which enter the chambers 10 and 13 prior to passing through the ports 2 into the engine cylinders.

Water is admitted through the conductor 42 into the chamber 6 and therein is converted 10 into steam which passes by the conductor 39 into the passage 32, where the steam is intermingled with the charges coming from the carbureters 33 and 34.

After the manifold has become heated, the 15 gasoline is cut off from the carbureter 34, following which oil enters the carbureter 33, after being admitted into the conductors 37, 36 and 38, the oil being heated in passing through the conductor 36.

20 The charge passes from the carbureter 33 into the passage 32, and thence by the paths already described entering the engine cylinders through the ports 2.

With my improved manifold, a maximum 25 of heating surface is afforded for heating the incoming charges with the exhaust gases discharged from the engine. Economy in the consumption of fuel is thus obtained and a maximum of efficiency is afforded.

30 I do not limit my invention to the structure shown and described, as modifications, within the scope of the appended claims, may be made without departing from the spirit of my invention.

35 What I claim is:—

1. In a manifold for explosive engines, a casing having two chambers and provided with a passage having two branches respectively discharging into said chambers, a 40 conductor for the explosive mixture discharging into said passage, the casing having at one side of said chambers a chamber for receiving water, the casing being provided at each side of said two chambers 45 with an inlet port for exhaust gases, the casing having an outlet port for exhaust

gases, and provided with a passage connecting said inlet ports with the outlet port and in which said two chambers and the passage having the two branches are located. 50

2. In a manifold for explosive engines, a casing having a longitudinal partition forming a compartment for water having an inlet for water and an outlet for steam at one side of said partition, the casing having two 55 longitudinal partitions parallel with the first named partition, transverse partitions connecting said first named partition with the two longitudinal partitions so as to form therewith two chambers, a conductor having two branches respectively discharging into said two chambers, a transverse partition extending from the first named partition to said conductor and forming two central chambers intermediate of the first two chambers, the casing having ports respectively of said two first named chambers with two 60 ports, a passage connecting the last named ports and said outlet port, and four passages connected with the last named passage and embracing said two branches and communicating with the two central chambers. 65

3. A manifold for explosive engines comprising a casing having two chambers respectively provided with outlet ports, a conductor having two branches respectively connected with said chambers for conveying 80 thereto the explosive charges, the casing having inlet ports disposed two at opposite sides respectively of each of said chambers, a passage connecting the two outer inlet ports, an outlet port communicating with 85 said passage, and passages connecting said passage with the two inner inlet ports and embracing said conductor and its two branches.

In testimony whereof I have signed my 90 name to this specification.

GEORGE H. HAYES.
